UNITED STATES PATENT OFFICE.

JOHN WHITE JOHNSTON, OF ROCHESTER, NEW YORK.

SHOE-CLEANING DEVICE.

Application filed May 4, 1898. Serial No. 636,640.

To all whom it may concern:

Be it known that I, JOHN W. JOHNSTON, a citizen of the United States, residing at Rochester, in the county of Monroe and

5 State of New York, have invented certain new and useful Improvements in Shoe-Cleaning Devices; and I do declare the following to be a full, clear, and exact description of the invention, such as will enable 10 others skilled in the art to which it appertains to make and use the same.

My invention has for its object to provide an extremely simple and inexpensive, yet a highly efficient and desirable device for 15 cleaning white shoes or other desired articles, the device embodying both a container for a cleaning powder and means for distributing and rubbing this powder onto the article to be cleaned.

20 With the foregoing in view, the invention resides in the novel subject matter hereinafter described and claimed, the description being supplemented by the accompanying drawing.

25 Figure 1 is a side elevation of a cleaning device constructed in accordance with my invention.

Figure 2 is a vertical longitudinal sectional view.

30 Figure 3 is an end elevation.

Figure 4 is a transverse sectional view on line 4—4 of Fig. 1.

In the drawing above briefly described, 35 the numeral 1 designates a suitably shaped

elongated body of hollow formation to contain a cleaning powder 2, one end of said body being formed with a filling opening 3 normally closed by a cork or the like 4, while the other end of said body is open.

40 Extending across this open end of the body 1, is a flat cushion 5 of wool, felt or other desired material, this cushion being perforated, for instance by having a comparatively large central opening 6, to permit the

45 discharge of powder. A layer of loosely woven material 7 extends over the outer side of the cushion 5 and has a loose pile 8 on its outer side, serving to effectively dis-

tribute the powder sifting through the material 7, as well as constituting an effective rubber for performing the cleaning operation.

The numeral 9 designates an adhesive band which surrounds the edge portion 10 of the layer 7 and laps onto the periphery of the 55 body 1, said edge 10 being turned around the end of the body as shown clearly in Fig. 2. It will thus be seen that the adhesive strip 9 will effectively secure the layer 7 to the body 1 and will also assist in holding 60 the cushion 5 in place. This cushion however is preferably glued to the body also.

By providing the construction shown and described, a device is provided which is of extreme simplicity and may therefore be 65 inexpensively manufactured and marketed, yet this article is an effective cleaner for white shoes or other articles. In order to effect the cleaning operation, it is simply necessary to shake the body until a quantity 70 of the cleaning powder sifts out into the loose pile 8 of the fabric layer 7, whereupon the device may be rubbed upon the article being cleaned, thus effectively distributing the cleaning powder and successfully performing the cleaning operation. After once 75 starting this operation, it is not necessary to further shake the body 1, as the rubbing operation causes the powder to work out in adequate quantity to produce the desired 80 results.

I claim:

A shoe cleaning device comprising an elongated hollow powder containing body open at one end, and closing means for 85 said open end of the body consisting solely of a thick perforated yieldable pad contacting with the body and yieldable freely into the open end thereof, a layer of loosely woven fabric over the outer side of the pad 90 with its edge turned around the periphery of said pad and body, and means securing said turned edge of the fabric to the body.

In testimony whereof I have hereunto affixed my signature.

JOHN WHITE JOHNSTON.
